UNITED STATES PATENT OFFICE.

WILFRED I. OHMER, OF DAYTON, OHIO, ASSIGNOR TO THE RECORDING AND COMPUTING MACHINES COMPANY, OF DAYTON, OHIO, A CORPORATION OF OHIO.

FARE REGISTER AND RECORDER.

No. 923,692.

Specification of Letters Patent.

Patented June 1, 1909.

Original application filed December 27, 1904, Serial No. 238,396. Divided and this application filed February 6, 1905. Serial No. 244,285.

To all whom it may concern:

Be it known that I, WILFRED I. OHMER, a citizen of the United States, residing at Dayton, in the county of Montgomery and State 5 of Ohio, have invented certain new and useful Improvements in Fare Registers and Recorders, of which the following is a specification, reference being had therein to the accompanying drawings.

10 This invention relates to fare registers and recorders, the application being a division of an application filed by me December 27, 1904, Ser. No. 238,396. In the said prior application I have set forth a machine comprising a group of printing counters actuated by the registering mechanism of the machine to give the detail totals of different kinds or classes of fare, and a printing wheel coöperating with said printing counter to print at 15 each station a record of the fares collected between stations, the printing counters being set to zero after the printing of each record, and the operation of setting said counters to zero also serving to actuate the printing wheel to advance it one step, so as to print the name of the next station on the next record.

20 My present invention has for its object to combine with these printing counters and printing wheel an indicator which is operatively connected with the printing wheel so as to move in unison therewith and indicate the name of the next station, which name the printing wheel is in position to print 25 upon the record, provision being made of means for simultaneously resetting to zero the printing counters and at the same time shifting the printing wheel and indicator.

25 In its preferred form, the invention includes within its scope mechanism for automatically reversing the direction of movement of the station printing wheel and station indicator after a predetermined number of actuations thereof, so that in case the 30 route to be traveled is one traversed alternately in opposite directions, the printing wheel and indicator will be automatically actuated to correspond with the actual order in which the stations are encountered.

35 To these and other ends my invention consists in certain novel features which I will now proceed to describe, and will then particularly point out in the claims.

40 In the accompanying drawings, Figure 1 is a front elevation of a fare register and re-

corder embodying my invention in one form, portions of the outer casing being broken away to show the internal construction; Fig. 2 is a side elevation, with the casing removed, of so much of the mechanism as is necessary 60 to an understanding of my present invention; Fig. 3 is an enlarged detail plan section of a portion of the actuating and reversing mechanism; Fig. 4 is an enlarged detail view of the actuating mechanism shown in Fig. 2, 65 viewed from the same direction, with the resetting key shown in position in section; Fig. 5 is a detail sectional view, taken on the line x x of Fig. 3 and looking in the direction of the arrows, the same being on a somewhat 70 reduced scale; Fig. 6 is a detail view of a portion of Fig. 5; and Fig. 7 is a detail view of the detent coöperating with the station printing wheel.

75 In the said drawings, 1 indicates a suitable inclosing casing, within which is mounted a frame or support 2, carrying the various mechanisms.

80 3 indicates a shaft supported in suitable bearings 4 on the frame or support 2, on which shaft are mounted a plurality of printing counters 5, each counter composed of number printing wheels and relating to a specific class or kind of fare, each counter being operated by suitable selective and actuating 85 mechanism so as to print a record of the total number of fares of that class when such record is taken therefrom by means of a suitable printing mechanism. These counters are so connected with the shaft as to move freely 90 thereon when actuated by the registering mechanism during the registering of the fares, while rotation of the shaft in the proper direction will reset all of the counters theron to zero, any of the well known constructions for this purpose being employed. I prefer to effect this rotation of the shaft 3 95 by means of a suitable key, which may be applied to the end of the shaft through an aperture in the casing, the shaft being provided 100 with a pin or projection 6, and the barrel of the key, shown in section at 7 in Fig. 4, having a slot 8 to engage the pin 6.

105 The station printing wheel is indicated at 9, the same being a wheel having printing characters thereon corresponding to the designations and arranged in the order of the stations, illustrated in the present instance as type letters adapted to print upon the record the names of the stations of the par- 110

ticular line on which the register is used. Secured on the shaft 3 near its left hand end is a crank arm 10, provided with an outwardly extending pin 11.

5 12 indicates a vibrating lever, comprising a central hub or sleeve 13, by means of which it is pivoted on a stud 14, mounted on a supporting arm 15 forming a part of one of the bearings 4. One end of this lever is formed 10 into a cam yoke 16, in which the pin 11 travels, and by contact with the inner wall of which said pin, during each complete rotation of the shaft 3, vibrates the lever 12 from the position shown in full lines in Fig. 4 to 15 the position shown in dotted lines in said figure, and then back to its original position, shown in full lines. The opening in said cam yoke is sufficiently large to permit the lever 12 to vibrate in the manner described, and 20 at the same time permit the shaft 3 to be extended through the cam yoke in order to receive the operating key. As shown, the cam yoke has opposite slots 17 and 18, with which the pin 11 successively engages during 25 the downward and upward movement of the cam yoke respectively, and intermediate cam contact surfaces 19, with which said pin contacts during certain portions of its travel. The lever 12, has on the other side of its pivot 30 axis from the cam yoke, a portion 20, which is slotted, as shown at 21, to receive a pin 22, carried by a pawl-supporting arm 23. This pawl-supporting arm is located on the inner side of the support 15 on which the 35 lever 12 is mounted, and is hung loosely upon the shaft 3 at its forward end, as indicated at 24. Upon the inner face of the pawl-supporting arm 23 there is mounted a bearing stud 25, on which is pivotally mounted a pawl 26, 40 which is a double pawl having two engaging arms 27 and 28, and another arm 29, extending in the opposite direction from the pivot stud 25, and having its extremity formed into oppositely inclined or beveled contact surfaces 30 and 31, as shown in Fig. 5. The 45 pawl-supporting arm 23 also carries a spring detent 32, mounted to slide in a housing 33 on the arm 25 and backed by a spring 34 in said housing. The projecting end of this 50 pin 32, which coöperates with the arm 29 of the pawl 26, has its end also formed into a double incline or bevel, the surfaces of which are indicated by the reference numerals 35 and 36, said detent lying in the path of the 55 end of the arm 29. There is connected to or formed on the hub of the station printing wheel 9 a ratchet wheel 37, the teeth of which are preferably of equal inclination to the radius, and with these teeth either one of the 60 pawl arms 27 or 28 may be brought into engagement. There is also secured to or formed on the hub of the wheel 9 a cam disk 38, having a cam projection 39, in the path of which lies an arm 40, connected to the

pawl 26 so as to move in unison therewith. 65 The wheel 9 is also provided with a detent ratchet wheel 41, engaged by a detent pawl 42 controlled by a spring 43, as shown more particularly in Fig. 7. This detent mechanism serves to hold the station printing wheel 9 in any position to which it may be moved by its actuating mechanism, and to prevent accidental displacement of said wheel. 70

By reason of the mechanism just described, each time the shaft 3 is rotated to reset to 75 zero the printing counters controlled thereby, a complete vibration will be imparted to the lever 12, and from it through the pin 22 to the pawl-supporting arm 23.

Assuming that the parts are in the position 80 shown in Fig. 5, the pawl arm 27 being in engagement with the ratchet wheel 37, the first or downward movement of the pawl-supporting arm will cause the pawl to rotate the ratchet wheel, advancing it one step, and 85 moving the name of the next station into printing position. During the return or upward movement of the pawl-supporting arm, the pawl arm 27 will slip over the teeth of the ratchet wheel 37, the detent 32 yielding sufficiently to permit this, and returning the pawl arm 27 to proper engaging position with the teeth of the ratchet wheel 37, in which position the spring of said detent holds said pawl arm during its operative or downward 90 strokes. The parts are so constructed and arranged that the arm 29 of the pawl does not swing past the central line of the detent during these operations, and the bearing surface 35 of the detent remains in contact with the bearing surface 30 of the arm 29 of the 95 printing wheel 9. At the end of the first half of the trip, the conductor having reset the 100 printing counters on the shaft 3 at each station, station printing wheel 9 will have made one complete revolution, or so much of a revolution as is necessary to print successively the names of all the stations. The cam projection 39 then comes into contact with the 105 arm 40, and rocks said arm and the pawl 26 upon their common pivot to an extent such as to cause the arm 29 of said pawl to pass the center line of the detent 32, bringing the 110 surface 36 of said detent into contact with the surface 31 of the arm 29, and throwing the pawl arm 28 into engagement with the ratchet wheel 37, at the same time throwing the pawl arm 27 out of engagement with said 115 wheel. The further vibrations of the lever 12 and pawl-supporting arm 23 will cause the ratchet wheel 37 and station printing wheel 9 to rotate in a direction opposite to that in which they rotated during the first half of the trip, so that the station names will be printed 120 in the reverse order during the return portion of the trip. Of course, it will be understood 125 that this reversing mechanism may be dis-

pensed with where the register is used in connection with a route over which the travel is not reversed, as on a belt or circuit line.

The mechanism just described is also employed to operate a station indicator as well as a station printing wheel, either alone or in connection with a station printing wheel, and, in Figs. 1 and 2, I have illustrated a construction in which a station indicating wheel 44 is mounted upon brackets 45, connected to an upward extension of the frame 2. This station indicating wheel is operated by a lever 46, which is connected by a link 47 with the member 20 of the lever 12, so as to move in unison therewith. The lever 46 corresponds in function to the member 20 of the lever 12, and, through a mechanism similar to that just described, imparts to the station indicating wheel 44 the same intermittent rotary motion, reversed at fixed intervals, which is imparted to the station printing wheel 9. The station indicator has placed thereon the names or designating characters of the several stations in their proper order, that one of the same which is in proper position being visible through an opening 48 in the casing 1. It will thus be seen that the resetting of the printing counters to zero not only advances the station printing wheel one step, but also advances the station indicator one step, so that the act of the conductor in resetting the printing counters at each station after taking a record therefrom operates the station indicator so as to cause it to indicate the next station.

It is obvious that various modifications in the construction may be made without departing from the principle of my invention. For instance, the station printing wheel may be omitted under certain circumstances, in which case the resetting to zero of the printing counter will actuate the indicator in the manner already described, reversing it automatically at the end of the run.

Other modifications will readily occur to those skilled in the art, and I therefore do not wish to be understood as limiting myself to the precise details of construction hereinbefore described and shown in the accompanying drawings.

I make no claim in the present application to the combination of station printing wheel, the fare printing counters, and the mechanism whereby the resetting to zero of the printing counters advances the station printing wheel and reverses its direction of rota-

tion after a predetermined number of actuations, as the same is claimed in my prior application No. 238,396, hereinbefore referred to, of which this is a division.

Having thus fully described my invention, what I claim as new and desire to secure by Letters Patent is:

1. In a machine of the character described, fare printing counters, a printing wheel, an indicator operatively connected with the printing wheel to move in unison therewith, and means for simultaneously resetting to zero the printing counters and advancing one step the printing wheel and indicator, said means comprising mechanism for reversing the direction of movement of the printing wheel and indicator after a predetermined number of actuations thereof, substantially as described. 75

2. In a machine of the character described, station record printing wheels comprising printing counters and a station printing wheel, a station indicator operatively connected with the station printing wheel to move in unison therewith, and means for simultaneously resetting to zero the printing counters and advancing one step the station printing wheel and station indicator, said means comprising mechanism for reversing the direction of movement of the station printing wheel and station indicator after a predetermined number of actuations thereof, substantially as described. 80

3. In a machine of the character described, fare printing counters, an indicator, and means for simultaneously resetting to zero the printing counters and advancing one step the indicator, in combination with means for reversing the direction of movement of the indicator after a predetermined number of actuations thereof, substantially as described. 90

4. In a machine of the character described, printing counters for producing a station record, a station indicator, and means for simultaneously resetting to zero the printing counters and advancing the station indicator one step, in combination with means for reversing the direction of motion of the station indicator after a predetermined number of actuations thereof, substantially as described. 100

In testimony whereof, I affix my signature in presence of two witnesses.

WILFRED I. OHMER.
